METHOD OF AND MEANS FOR BENDING
TUBES

Lester W. Snell, Alton, Ill.

Application July 25, 1932, Serial No. 624,405

17 Claims. (Cl. 153—32)

This invention relates to methods of and means for bending tubes, and the novel features may be advantageously used in making pipe fittings, such as U-shaped return bends, elbows with end portions at various angles to each other, and also in making long continuous coils of tubing.

In performing an ordinary simple bending operation, a metal tube is stretched at the arc of greatest radius which is termed the outer portion of the bend, while the metal is compressed at the inner portion of the bend, where the radius of the curve is shorter. The stretching in this old method reduces the thickness of the metal at the outer portion of the bend, while the compression increases the thickness at the inner portion of the bend. As a consequence, the ordinary simple bending operation results in a bent tube that is non-uniform in thickness.

One of the objects of this invention is to bend the tubes while preventing undesirable variations in the thickness of the tube walls.

Another object is to accurately bend the tubes to a predetermined curvature and diameter.

A further object is to provide the bent tube with a smooth and uniform circular outer face.

With the foregoing and other objects in view, the invention comprises the novel method, construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. 1 is a section illustrating a bending system embodying the features of this invention.

Fig. 2 is a transverse section on the line 2—2 in Fig. 1, showing variations in the thickness of the tube to be bent.

Fig. 3 is a section on the line 3—3 in Fig. 1, showing the uniform thickness of the bent tube.

Fig. 4 is a section on the line 4—4 in Fig. 1.

Fig. 5 is a section on the line 5—5 in Fig. 1.

Fig. 6 is a side elevation on a smaller scale showing a hammer-operating device.

Fig. 7 is a section taken approximately on the line 7—7 in Fig. 6.

Fig. 8 is a section taken approximately on the line 8—8 in Fig. 6.

The apparatus shown to illustrate one form of the invention comprises a forming die 9 made of two sections contacting with each other at the line 10 in Fig. 5, and alined by means of dowel pins 11, said die having a curved passageway 12,

through which the tube to be bent is forced to give the desired curvature.

13 indicates a tube adapted to be forced through the passageway 12. In the preferred form of the invention, the first step comprises forming a continuous straight tube of any desired length of a cross section, such as shown by Fig. 2. This straight tube has a relatively thick portion which extends longitudinally of the tube, and the thickness gradually decreases circumferentially to a point diametrically opposite said thick portion.

In other words, as shown in Fig. 2, the thick portion of the tube to be bent lies directly opposite the thin portion, and there is a gradual change in thickness between these portions, the inner face of the tube being eccentric to the outer face. After the tube has been forced through the curved passageway 12, it is curved as shown at the left of Fig. 1, and it has a uniform thickness, as shown in Fig. 3. This uniformity in thickness of the bent tube is due partly to the non-uniformity in thickness of the material to be bent, and partly to the upsetting operation which occurs when the tube is bent.

14 designates a stationary guide tube (Fig. 1) extending from the entrance of the curved passageway 12 and conforming to the outer face of the straight portion of the tube 13. A heating chamber 15 surrounding the guide tube 14 may be covered with insulation 16 and provided with inlet and exhaust pipes 17 and 18 for the admission and discharge of the heating medium, which may be a highly heated gas or other suitable heating agent. The heat transmitted from this chamber 15 may be great enough to subject the tube 13 to a substantially uniform red heat while it passes through the guide tube 14.

The thickest portion of the tube 13 passes from the guide tube 14 to the curve of largest radius in the curved passageway 12, as shown in Fig. 1, while the thinnest portion in said tube passes through the curve of shortest radius in said passageway.

The tube 13 may be pushed through the guide 14 by any suitable power and is gradually heated to a uniform high temperature by the heat transmitted from the surrounding chamber 15.

A local cooler 19 is located at the entrance to the curved passageway 12 so that the thickest portion of the tube to be bent is subjected to a cooling action as it passes to the bending zone in the curved passageway 12.

As shown by Fig. 4, the local cooler 19 may be

provided with inlet and discharge pipes 20 and 21 through which a cooling fluid is transmitted.

The bending zone in the curved passageway 12 extends approximately from the entrance of said 5 passageway to a position near the point designated by 22. The curved passageway is preferably tapered as suggested by dimensions appearing in Fig. 1. It is larger in diameter at the bending zone than the diameter of the tube to be bent, and 10 slightly smaller in diameter beyond the bending zone than the diameter of the passageway at the bending zone.

The decrease in diameter of the passageway 12 beyond the bending zone will eliminate the slight 15 flattening which occurs at the inner arc of the tube where the pressure tends to force the tube away from the face of the die, and this feature also provides the tube with a smooth and uniform circular outer face.

20 A hammer 23 having a curved portion 24 is located in the curved passageway 12. The hammer is provided with a straight portion 25 extending into the straight passageway 14. The diameter of the straight portion 25 of the hammer is approximately equal to the internal diameter of the tube to be bent, and the curved portion 24 of said hammer is smaller than the internal diameter of the tube as it passes the curved portion of the hammer.

30 In the drawings I have shown a device for reciprocating the hammer in the passageways 12 and 14. However, it is to be understood that any other suitable means could be used to operate the hammer.

35 The device as shown comprises a rod 26 having a head 27 which is located in a chamber 28 in the straight portion 25 of the hammer, as shown in Fig. 1. The head 27 on the rod 26 is adapted to strike the walls 29 and 30 of the chamber 28 40 to force the hammer backward and forward in the passageways 12 and 14.

45 The rearward portion of the rod 26 is adapted to receive arms 31 which are pivotally secured to a shaft 32 and held in position by the collars 33. The lower portions of the arms 31 are in the form 50 of hooks 34 and, as shown in Fig. 1, these hooks are detachably secured to the rod 26. Collars 35 are located on the rod 26 at opposite sides of the arms 31 to provide for the transmission of movement from the arms 31 to said rod 26.

55 The shaft 32 is slidably supported in hangers 36 and 37. A spring 38 is located on the shaft between the hanger 37 and a spring seat 39. This spring will tend to hold the shaft 32 and rod 26 60 in their rearward positions.

To provide for the reciprocation of the shaft 32 and rod 26, I have shown bevel gears 40 and 41 through which power is transmitted from a motor 42 to a cam 43. A collar 44 which is secured 65 to the shaft 32 by a set screw 45, has a projection 46 which lies in the path of the cam 43. As the cam 43 rotates, the extended portion 47 of the cam will force the projection 46 on the collar together with the shaft 32 and rod 26 forwardly, and after the extended portion of the cam passes the projection 46 on the collar, the spring 38 will 70 force the shaft 32 and rod 26 to a rearward position. Since the hammer 23 is operatively secured to the rod 26, it will likewise be reciprocated by the cam 43 and spring 38.

75 The curved portion 24 of the hammer (Fig. 1) is provided with a curved face 48 conforming to the curvature of the inner face of the arc of relatively large radius of the bent tube.

The curved portion 24 of the hammer is also provided with another curved face 49 conforming to the curvature of the inner face of the arc of relatively small radius of the bent tube.

The curved face 48 of the hammer provides a 5 cam which forces the tube onto the curve of largest radius in the curved passageway at the completion of the forward stroke of the hammer, and at the same time forces a portion of the hammer in the straight passageway onto the portion of the tube approaching the bending zone at the arc of smallest radius.

The curved face 49 of the hammer provides a 10 cam which forces the tube onto the curve of smallest radius in the curved passageway at the 15 completion of the rearward stroke of the hammer, and at the same time forces a portion of the hammer in the straight passageway onto the portion of the tube approaching the bending zone at the 20 arc of largest radius.

To prevent overheating of the hammer, I have shown a passageway 50 extending from the chamber 28 in the hammer to the forward end of the hammer. The rod 26 has a passageway 51, and the head 27 on said rod is provided with passage- 25 ways 52 which communicate with the passageway 51 and the chamber 28. Air or other cooling medium may, therefore, be forced from any suitable source (not shown) through the passageway 51 in the rod 26, and through the passage- 30 ways 52, chamber 28 and passageway 50 to provide the desired cooling of the hammer.

The chamber 28 in the straight portion of the hammer is preferably surrounded by insulation 53 to retard the transmission of heat from the 35 heating chamber 15 to the chamber 28 where the head 27 on the rod 26 strikes the walls 29 and 30.

The operation of the parts so far described will 40 be briefly set forth as follows:

The arms 31 are detached from the shaft 32 and a tube 13 having an external diameter of 3.392 and a cross section, such as shown in Fig. 2, may be placed onto the rod 26. The arms 31 are then 45 replaced in position and the tube forced by any suitable means (not shown) through the straight passageway 14 and the curved passageway 12.

Additional tubes 13 may be delivered to the 50 apparatus, as shown by dotted lines in Fig. 6, and the bending operations may be carried out continuously for an indefinite period. Each tube, excepting the first, pushes a preceding tube entirely through the bending die, and the bent tubes are discharged from the apparatus in the 55 form of elbows, return bends, or the like, depending upon the length of the straight tube sections delivered to the apparatus.

When the tube passes through the straight passageway 14, it may be heated to a substantially 60 uniform red heat by the heat transmitted from the heating chamber 15. As the tube passes to the bending zone, the thickest portion of the tube is subjected to a cooling action at the local cooler 19 to prevent substantial upsetting of the relatively thick portion of the tube in the bending zone.

When the tube enters the bending zone it is 65 preferably enlarged so that it will have an external diameter slightly greater than 3.5 inches.

When the tube is forced through the bending 70 zone of the curved passageway 12, it has a tendency to depart from the arcuate faces of the passageway. This tendency is the greatest at the smallest or inner arc of the curved passageway where the forward motion of the tube tends 75

to produce a bridging action and thus separate the tube from the inner arc of the curved passageway.

The hammer 23 is reciprocated while the tube is passing through the bending zone. When the hammer reaches the end of its forward stroke, its curved face 48 will strike the tube on its inner face at the arc of relatively large radius and force this portion of the tube onto the relatively large arc of the curved passageway.

The curved face 48 of the hammer will also provide a cam action on the face of the tube, to force the straight portion 25 of the hammer onto the thin portion of the tube to prevent buckling of the relatively hot thin metal approaching the bending zone.

After the completion of the forward stroke of the hammer 23, the curved face 48 of the hammer will remain in contact with the inner face of the tube while the head 27 on the rod 26 travels from the wall 29 of the chamber 28 to the wall 30. This period of time, however, is relatively short as the spring 38 immediately withdraws the rod 26 when the extended portion 25 of the cam 43 passes the projection 46 on the collar 44.

At the completion of the rearward stroke of the hammer 23, the curved face 49 of the hammer will force metal of the tube at the curve of small radius onto the face of the curved passageway having a relatively small radius, to prevent any bridging action which might separate the tube from the inner or relatively small arc of the die.

The curved face 49 of the hammer 23 will at this time provide a cam action against the inner face of the tube at the arc of relatively small radius to force the straight portion 25 of the hammer onto the thick straight portion of the tube to prevent irregular separation of this portion of the tube from the wall of the straight passageway.

After the completion of the rearward stroke of the hammer there is a relatively long time interval during which the curved face 49 of the hammer remains in contact with the tube. This interval is due to the fact that the cam must travel a relatively long distance before it again forces the hammer forward.

The curved faces 48 and 49 of the hammer conform to the curvatures desired in the bending zone. The inner faces of the tube at the relatively large and small arcs will, therefore, be given the desired curvature during the hammering action in the bending zone.

In the form of the invention disclosed wherein the tube is enlarged in the bending zone, the curved portion 24 of the reciprocating hammer will also aid in enlarging the tube by forcing it onto the walls of the curved passageway.

After the tube passes from the bending zone it is slightly contracted to a diameter of approximately 3.5 inches in the curved passageway 12 to insure a smooth and uniform circular outer face.

When the tube, as illustrated in Figs. 1 and 3, passes from the die, the walls of the tube will have a uniform thickness of approximately 0.216, an external diameter of 3.5 and an internal diameter of about 3.68.

In the foregoing description, specific dimensions have been given. However, these dimensions have been given to merely illustrate one form of my invention, and they do not in any way limit the scope of the invention.

I claim:

1. The method of producing curved tubes

which comprises heating a tube, bending said tube while forcing the same through a curved passageway, hammering the inner face of the arc of relatively large radius of the tube during said bending operation to force the tube onto the curved face of the largest radius in said passageway, and hammering the inner face of the arc of relatively small radius of the tube during said bending operation to force the tube onto the curved face of smaller radius in said passageway.

2. The method of producing curved tubes which comprises heating a tube, bending said tube and enlarging the diameter thereof while forcing said tube through a curved passageway, hammering the inner face of the arc of relatively large radius of the tube during said bending operation to force the tube onto the face of largest radius in said passageway, hammering the inner face of the arc of relatively small radius of the tube during said bending operation to force the tube onto the curved face of smaller radius in said passageway to prevent a bridging action of the material at the curve of smallest radius, and to aid in enlarging the diameter of the tube, cooling the relatively thick portion of the tube to check an upsetting action in said thick portion, and then slightly contracting said tube to provide the tube with a substantially smooth and uniform circular outer face.

3. The method of producing curved tubes which comprises forming a tube with a relatively thick portion longitudinally of the tube, the thickness decreasing circumferentially to a point diametrically opposite said thick portion, heating said tube, bending said tube and enlarging the diameter thereof by forcing said tube through a curved passageway, and hammering the arcs of relatively large and small radii of the tube during said bending operation.

4. The method of producing curved tubes which comprises forming a tube with a relatively thick portion longitudinally of the tube, the thickness decreasing circumferentially to a point diametrically opposite said thick portion, heating said tube, bending said tube and enlarging the diameter thereof by forcing said tube through a curved passageway, hammering the inner face of the arc of relatively large radius of the tube during said bending operation to force the tube onto the curve of largest radius in said curved passageway, hammering the inner face of the arc of relatively small radius of the tube during said bending operation to force the tube onto the curve of smaller radius in said passageway, to prevent a bridging action of the tube at the curve of smallest radius and to aid in enlarging the diameter of the tube, cooling the relatively thick portion of the tube during said bending operation to check an upsetting action in said thick portion, and then slightly contracting the diameter of the bent tube to provide the tube with a substantially smooth and uniform circular outer face.

5. In a tube bending apparatus, a bending die having a curved passageway through which the tube is forced to form the desired bend, said curved passageway having a larger diameter at the bending zone than the diameter of the tube to be bent, so as to enlarge the tube during the bending operation, and means whereby the tube is forced entirely through and discharged from said curved passageway.

6. In a tube bending apparatus, a bending die having a curved passageway through which the tube is forced to form the desired bend, a curved hammer secured within said passageway so as to

- remain at the bending zone therein, and means whereby said hammer is forced onto the inner face of the bend of largest radius of the tube to force the tube onto the arc of largest radius of the curved passageway.
7. In a tube bending apparatus, a bending die having a curved passageway through which the tube is forced to form the desired bend, a curved hammer secured within said passageway so as to remain at the bending zone therein, and means whereby said hammer is forced onto the inner face of the bend of relatively small radius in the tube to force the tube onto the corresponding portion of the curved passageway.
8. In a tube bending apparatus, a bending die having a curved passageway through which the tube is forced to form the desired bend, a hammer secured in said passageway so as to remain at the bending zone therein, and means whereby said hammer is reciprocated to alternately force the tube onto oppositely disposed faces of said curved passageway.
9. In a tube bending apparatus, a bending die having a curved passageway through which the tube is forced to form the desired bend, said curved passageway having a larger diameter at the bending zone than the diameter of the tube to be bent, said curved passageway being slightly smaller in diameter beyond the bending zone than the diameter of the passageway at the bending zone, a hammer having a curved portion located in said curved passageway, said curved portion of the hammer being provided with a cam face adapted to force the tube onto the curve of largest radius in the curved passageway at the completion of the forward stroke of the hammer, and means whereby said hammer is reciprocated in said passageway, said curved hammer providing a cam face adapted to force the tube onto the curve of smallest radius in the curved passageway at the completion of the rearward stroke of the hammer.
10. In a tube bending apparatus, a bending die having a curved passageway through which the tube is forced to form the desired bend, a cylindrical housing communicating with said curved passageway, said cylindrical housing having a straight passageway conforming to the external diameter of the tube to be bent, a hammer having a curved portion located in said curved passageway, said hammer being provided with a straight portion extending into said straight passageway, the diameter of said straight portion of the hammer being approximately equal to the internal diameter of the tube to be bent, said curved passageway being slightly smaller in diameter than the internal diameter of the tube passing the curved portion of the hammer, and means whereby said hammer is reciprocated in said passageway, said curved hammer providing a cam face adapted to force the tube onto the curve of largest radius in the curved passageway at the completion of one stroke of the hammer, said curved hammer also providing a cam face adapted to force the tube onto the curve of small radius in the curved passageway at the completion of another stroke of the hammer.
11. In a tube bending apparatus, a bending die having a curved passageway through which the tube is forced to form the desired bend, a curved hammer secured within said passageway so as to remain at the bending zone therein, and means whereby said hammer is forced onto the inner face of the bend of relatively small radius in the curved passageway while forcing a portion of the hammer in the straight passageway onto the portion of the tube approaching the bending zone at the arc of smallest radius, said curved hammer also providing a cam face adapted to force the tube onto the curve of relatively small radius in the curved passageway while forcing a portion of the hammer in the straight passageway onto the portion of the tube approaching the bending zone at the arc of largest radius.
12. The method of producing curved tubes which comprises bending a traveling tube while forcing successive portions of said tube entirely through a curved bending zone to form a curved bend in the tube, and at the same time forcibly smoothing successive portions of the curved bend by transmitting them from said curved bending zone, through a correspondingly curved contracting zone and forcibly reducing the diameter of said curved bend as it travels through said curved contracting zone, said curved bend being transmitted entirely through said curved contracting zone to produce a curved tube having a substantially smooth and uniform outer face.
13. The method of producing curved tubes which comprises bending and increasing the diameter of a traveling tube while forcing successive portions of said tube entirely through a curved bending zone to form a curved bend in the tube, and at the same time forcibly smoothing successive portions of the curved bend by transmitting them from said curved bending zone, through a correspondingly curved contracting zone and forcibly reducing the diameter of said curved bend as it travels through said curved contracting zone, said curved bend being transmitted entirely through said curved contracting zone to produce a curved tube having a substantially smooth and uniform outer face.
14. The method of producing curved tubes which comprises bending a tube by forcing it through a curved passageway, and continually hammering the inner face of the tube during the bending operation by striking hammer blows on the curves of relatively large and small radii formed in the bent portions of the tube, so as to hammer said bent portions onto the oppositely disposed faces of said curved passageway.

15. The method of producing curved tubes which comprises bending a tube by forcing it entirely through a curved passageway, and continually hammering the inner face of the tube by 5 striking alternate hammer blows on the curves of relatively large and small radii formed in the oppositely disposed bent portions of the tube, so as to alternately hammer said bent portions onto the oppositely disposed faces of said curved pas-
10 sageway.
16. In a tube-bending apparatus, a bending die having a curved passageway including an arcuate bending zone into which the tube is forced to form a correspondingly curved bend and an 15 arcuate contracting zone through which the curved bend is discharged, said curved passage-
way being contracted beyond said bending zone to reduce the diameter of the curved bend as it passes through said arcuate contracting zone.
17. In a tube-bending apparatus, a bending die having a curved passageway including an arcuate bending zone into which the tube is forced to form a correspondingly curved bend and an arcuate contracting zone through which the curved bend is discharged, the diameter of the bending zone in said curved passageway being 10 larger than the diameter of the tube to be bent, and said curved passageway being contracted beyond said bending zone to reduce the diameter of the curved bend as it passes through said arcuate contracting zone. 15

LESTER W. SNELL.
